CLAIM

I claim the ornamental design for a drain cover for shower receptor, as shown and described.

DESCRIPTION

FIG. 1 is a top, front, right perspective view of a first embodiment of the claimed design;

FIG. 2 is top plan view thereof;

FIG. 3 is a left elevation view thereof;

FIG. 4 is a right elevation view thereof;

FIG. 5 is a rear elevation view thereof;

FIG. 6 is a front elevation view thereof;

FIG. 7 is a top, front, right perspective view of a second embodiment of the claimed design.

FIG. 8 is top plan view thereof;

FIG. 9 is a left elevation view thereof;

FIG. 10 is a right elevation view thereof;

FIG. 11 is a rear elevation view thereof;

FIG. 12 is a front elevation view thereof;

FIG. 13 is a top, front, right perspective view of a third embodiment of the claimed design;

FIG. 14 is top plan view thereof;

FIG. 15 is a left elevation view thereof;

FIG. 16 is a right elevation view thereof;

FIG. 17 is a rear elevation view thereof; and,

FIG. 18 is a front elevation view thereof.

The ornamental design which is claimed is shown in solid lines in the drawings. The broken lines shown in the drawings depict portions of the article that form no part of the claim. Broken lines formed by equal length dashes show unclaimed subject matter. Broken lines formed of unequal length dashes (i.e., dash-dot) define bounds of the claimed design. Broken away symbols having a jagged element show that no particular length of the portion is claimed.
